UNITED STATES PATENT OFFICE.

JOSEPH H. PENGILLY, OF LOS ANGELES, CALIFORNIA, ASSIGNEE OF ONE-HALF TO BROWN & PENGILLY, OF LOS ANGELES, CALIFORNIA, A CORPORATION OF CALIFORNIA, AND ONE-HALF TO SAFETY ELECTRIC PRODUCTS COMPANY, OF LOS ANGELES, CALIFORNIA, A CORPORATION OF CALIFORNIA.

SERVICE SWITCH.

Application filed March 26, 1925. Serial No. 18,461.

This invention relates to electrical equipment, and it relates particularly to service switches. Service switches are employed in connecting a subsidiary circuit or a plurality of subsidiary circuits to a main circuit. A common type of service switch comprises a box in which a fuse block having a series of circuit fuse sockets in which fuses are placed. The various circuits are connected to the main lines by means of a switch which is operated by a lever. This switch in the common type of service switch is situated behind the fuse block and the knife contact thereof is swingable in a plane perpendicular to the front of the box. The wires of the various circuits which connect to the fuse block are generally extended behind the fuse block. These wires very often interfere with the operation of the switch and sometimes cause short-circuiting. The lever for operating this switch extends through the side of the box. For this reason these service switches cannot be set into the wall.

It is an object of my invention to provide a service switch having a novel switch arrangement which is so designed that circuit wires will not interfere with the operation thereof. I provide in my invention a switch which is positioned to the side of the fuse block and which has a knife contact which is swingable in a plane parallel to the front of the box. The wires being extended to the rear of the block will not interfere with the switch; therefore such difficulties present in the common type of service switch are eliminated.

It is also an object of my invention to provide a service switch which may be set into the wall. I accomplish this object of my invention by extending the operating means and the switch through the front of the box and not through the side. It is desirable to set a switch of this character in the wall, first, as a matter of appearance and, second, as a conservation of space.

It is another object of my invention to provide a service switch of the character mentioned which is very easy to wire. I provide a removable bridge on which the fuse block is secured. The block may be wired before installation in the box. This makes the wiring thereof very facile.

Another object of this invention is to pro-

vide a means for holding the circuit wires out of interference with the switch. The bridge of my invention has a raised portion under which the wires may be extended so that they cannot interfere with the switch. Another object of my invention is to provide a service switch of the character mentioned which will have a dead front. I provide a partition which is arranged to be secured inside the box over the fuse block. This partition has openings therein, giving access to the fuse sockets and an opening through which the switch operating knob extends. This partition covers all live wires.

Other objects and advantages of the invention will be made evident hereinafter.

Referring to the drawings in which I illustrate a preferred form of my invention.

Fig. 1 is a view looking at the front of the service switch embodying the features of my invention.

Fig. 2 is a view similar to Fig. 1 showing the cover of the box in open position.

Fig. 3 is an enlarged face view showing the fuse block, the partition being removed in this view.

Fig. 4 is a section taken on the line 4—4 of Fig. 3.

Fig. 5 is a section taken on the line 5—5 of Fig. 3.

Fig. 6 is a fragmentary view taken on the line 6—6 of Fig. 3 showing the construction of the stationary contact of the switch of my invention.

With reference to the drawings, a preferred form of my invention comprises a metallic box 11 having a cover 12 for closing the front 13 thereof, this cover 12 being hinged thereto at 14. Screws 15 extend through slots 16 in flanges 17 of a bridge 18, thereby securing the bridge 18 to the bottom 19 of the box 11. A fuse block 21 is secured to a raised portion 22 of the bridge 18 by screws 23 which extend into feet 24 of the block 21.

The block 21 provides a plurality of circuit fuse sockets 27. As clearly shown in Fig. 4, each of the fuse sockets 27 has a shell 28 which is placed in a cavity 29. Each shell 28 is secured in the cavity 29 by means of a screw 30 which extends through the lower portion of the block 21 and secures a contact plate 32 to the block 21. A

boss 33 is formed in each cavity 29 and extending through each boss 33 is a central stud 34 which extends through the block 21 and secures a bus-bar 35 in a recess 36 5 formed in the bottom of the block 21. My invention provides a single bus-bar 35 through which each of the central studs 34 extends. The end 38 of the bus-bar extends beyond the fuse block 21 and is adapted to have a wire attached thereto, as clearly shown in Figs. 3 and 5. The block 21 also provides a main fuse socket 40. As clearly shown in Fig. 4, the main fuse socket 40 provides a shell 41 which is retained in a cavity 42 by means of a screw 43 which secures a contact plate 44 to the block 21. A central stud 46 extends through a central boss 47 and secures a bar 48 to the lower face of the fuse block 21. A screw 49 is also provided to assist in securing the bar 48 in place.

A bolt 51 extends through an opening formed in the outer end of the bar 48, this bolt 51 extending through a clevis 52 for pivoting a knife 53 of a switch to the bar 48. The clevis 52 has legs 54 which extend to each side of the end of the bar 48. On the opposite end of the knife contact 53 there is formed a clevis 56 between which a stationary contact 57 extends when the switch is in closed position. An arm 58 is attached to the knife contact 53, this arm extending upwardly and having a knob 60 attached thereto, as clearly shown in Fig. 5. The knob 60 is placed concentrically with the point of pivot of the knife contact 53. The knob 60 is especially prepared so that the upper portion thereof is in the shape of an arrow 61, as clearly shown in Figs. 1 to 3, inclusive.

The stationary contact 57 is secured in a recess 64 formed in the lower face of the block 21 by screws 65 which extend through a flange 66 of the block 21. The rear portion of the stationary contact 57 is bent upwardly at 68 and extends through a slot 69 formed in the flange 66. The contact is bent horizontally at 70 through which portion 70 a screw 71 extends for securing a wire thereto.

Extending across the box 11 is a front or partition 75. This partition 75 is secured to the block 21 by means of nuts 76 which thread onto studs 77 extending from formations 78 of the block 21. The partition has an opening 80 through which the upper portions of the circuit sockets 27 and the main socket 40 extends, as clearly shown in Figs. 2 and 4 of the drawing. This partition 75 covers all of the wiring and contacts of the switch and prevents a person from touching a live part.

The cover 12 is depressed at 82 and has an opening 83 formed at the center of this depression. When the cover is closed, the

arrow portion 61 of the knob 60 extends through and may be operated from the exterior of the box.

One main line is connected to the stationary contact 57 by the screw 71. The other of the main lines is connected to a plate 85 by a screw 86. The plate 85 is secured in place, as shown in Fig. 5, by screws 87 which extend through the flange 66 of the fuse block 21. The plate 85 has a screw 88 by which a ground wire may be attached thereto, and has a screw 90 by which the wire extending from a meter may be attached. Current may pass into the service switch through the wire connected to the stationary contact 57. When the switch is closed, the current passes through the stationary contact 57, through the knife contact 53 and through the bar 48 to the main fuse socket 40. The current passes from the fuse socket 40 through the contact plate 44 which is associated with the shell 41.

A wire to the meter is connected to the contact plate 44 by a screw 92. A wire from the meter is connected to the end 38 of the bus-bar 35 by a screw 93. Current is supplied by the bus-bar 35 to each of the circuit fuse sockets 27. Current passes from each of the fuse sockets 27 through the contact plates 32. A screw 94 is provided for attaching a circuit wire to each of the contact plates 32. These circuit wires extend from the box 11 to devices where the current is utilized. The other circuit wires of these subsidiary circuits are extended into the box and connect to a contact plate 96 by means of screws 97. This contact plate 96 is secured to the flange 66 of the fuse block 21 by screws 98. A screw 99 is provided for securing a wire which extends from the meter to the contact plate 96.

The bridge 18 is removed by loosening the screws 15, and moving the bridge toward the top of the box so as to disengage the lower screws from their slots 16. The bridge is then moved downwardly and the upper slots 16 disengaged, thus freeing the bridge. The fuse block 21, due to the removability thereof, may be wired before its installation in the box 11. This makes the wiring thereof very easy. The circuit wires, if desired, may be extended through the space below the raised portion 22 of the bridge 18. The bridge 18 will hold these wires in place and prevent them from interfering with the switch.

The partition 75 entirely covers the live parts of the service switch and exposes only the circuit sockets and the main socket. The partition is marked "On" and "Off", as indicated at 100 and 101. The arrow on the knob 60 is arranged so that the switch is closed when it points to "On" and open when it points to "Off". The cover 12 is also marked "On" and "Off", as indicated 130

at 103 and 104. By such marking, it is possible to discern whether or not the switch of the service switch is open.

By providing a switch which works in a plane parallel to the front of the box, and by arranging it to the side of the fuse block, any interference thereto by the wires is eliminated. By arranging the knob 60 in the front of the box any extensions from the sides of the box are done away with and the box may be set in the wall. This is a very valuable feature, as the box may be set in an unobstructing place which is sometimes very desirable. By providing the depression 82 and the opening 83, the knob 60 may be conveniently operated even though the cover 12 is closed.

I claim as my invention:

1. In a service switch, the combination of: a box having a cover; a bridge secured inside said box; a fuse block secured to a raised portion of said bridge away from the back of said box, said fuse block comprising a plurality of circuit fuse sockets, a bus-bar associated with said circuit sockets, contacts associated with said circuit fuse sockets, a main fuse socket and a contact associated with said main fuse socket; a switch for connecting said circuit fuse sockets to main circuit lines, said switch comprising a blade secured to said fuse block, a swingable arm arranged to contact said blade, said arm being swingable in a plane parallel to the front of said box, and a knob whereby said arm is swung, said knob being situated inside said box; and a partition extending across said box above said fuse block and secured to said fuse block, there being openings in said partition above said circuit and main fuse sockets and an opening through which said knob extends.

2. In a service switch, the combination of: a box having a cover; a bridge secured inside said box; a fuse block secured to a raised portion of said bridge away from the back of said box, said fuse block comprising a plurality of circuit fuse sockets, a bus-bar associated with said circuit sockets, contacts associated with said circuit fuse sockets, a main fuse socket and a contact associated with said main fuse socket; a switch for connecting said circuit fuse sockets to main circuit lines, said switch comprising a blade secured to said fuse block, a swingable arm arranged to contact said blade, said arm being swingable in a plane parallel to the front of said box, and a knob whereby said arm is swung, said knob being situated inside said box, and a partition extending across said box above said fuse block and secured to said fuse block, there being openings in said partition above said circuit and main fuse sockets and an opening through which said knob extends.

said knob being situated inside said box and being enclosed by said cover; and a partition extending across said box above said fuse block, there being openings in said partition above said circuit and main fuse sockets and an opening through which said knob extends.

3. In a service switch, the combination of: a box having a cover; a bridge secured inside said box; a fuse block secured to a raised portion of said bridge away from the back of said box, said fuse block comprising a plurality of circuit fuse sockets, a bus-bar associated with said circuit sockets, contacts associated with said circuit fuse sockets, a main fuse socket and a contact associated with said main fuse socket; a switch for connecting said circuit fuse sockets to main circuit lines, said switch comprising a blade secured to said fuse block, a swingable arm arranged to contact said blade, said arm being swingable in a plane parallel to the front of said box, and a knob whereby said arm is swung, said knob being situated inside said box; and a partition extending across said box above said fuse block and secured to said fuse block, there being openings in said partition above said circuit and main fuse sockets and an opening through which said knob extends.

4. In a service switch, the combination of: a box having a cover; a bridge secured inside said box; a fuse block secured to a raised portion of said bridge away from the back of said box, said fuse block comprising a plurality of circuit fuse sockets, a bus-bar associated with said circuit sockets, contacts associated with said circuit fuse sockets, a main fuse socket and a contact associated with said main fuse socket; a switch for connecting said circuit fuse sockets to main circuit lines, said switch comprising a blade secured to said fuse block, a swingable arm arranged to contact said blade, said arm being swingable in a plane parallel to the front of said box, and a knob whereby said arm is swung, said knob being situated inside said box and being enclosed by said cover; and a partition extending across said box above said fuse block and secured to said fuse block, there being openings in said partition above said circuit and main fuse sockets and an opening through which said knob extends.

In testimony whereof, I have hereunto set my hand at Los Angeles, California, this 20th day of March, 1925.

JOSEPH H. PENGILLY.
